[57] CLAIM

The ornamental design for a lap mounted joystick holder, as shown and described.

DESCRIPTION

FIG. 1 is a reduced perspective view of a lap mounted joystick holder showing my new design;

FIG. 2 is an end elevational view thereof;

FIG. 3 is a top plan view thereof;

FIG. 4 is a front elevational view with portions broken away to clarify the support structure, the rear being substantially identical;

FIG. 5 is a bottom plan view thereof.
